UNITED STATES PATENT OFFICE.

HENRY D. WEGE, OF BARRE, WISCONSIN.

CONCRETE-MIXER.

1,260,840.

Specification of Letters Patent. Patented Mar. 26, 1918.

Application filed August 15, 1916. Serial No. 115,033.

To all whom it may concern:

Be it known that I, HENRY D. WEGE, a citizen of the United States, and a resident of Barre, in the county of La Crosse and 5 State of Wisconsin, have invented a certain new and useful Improvement in Concrete-Mixers, of which the following is a specification.

My invention is an improvement in concrete mixers, and has for its object to provide a device of the character specified, wherein a rotatable casing is provided having at one end a discharge opening, and a mixing vane on the inner face of the said 15 end, so arranged that when the casing is rotated in one direction, the vane will prevent the material passing out of the discharge opening, while when the casing is turned in the other direction, the vane will cause 20 the material to discharge from the discharge opening, and wherein the mixing is brought about solely by the rotation of the casing and the action of the said vane.

In the drawings:

25 Figure 1 is a front view of the improved mixer;

Figs. 2 and 4 are sections on the lines 2—2 and 4—4 respectively of Fig. 3, each view looking in the direction of the arrows adjacent to the lines;

30 Fig. 3 is a section on the line 3—3 of Fig. 2, looking in the direction of the arrows adjacent to the line.

The present embodiment of the invention 35 comprises a casing 1 of semicircular cross section, the said casing being substantially cylindrical and having its axis inclined with respect to the planes of its ends, as shown. This casing is supported by wheels 2 mounted 40 on axles 3 which are journaled in bearings 4 having upward extensions 5 to which are connected channel bars 6, the said bars being arranged with their channels inward. An arc-shaped guide member 7 is secured 45 to the channel bars near the axle, the said guide being channel-shaped and the casing is supported by the guide. This guide is approximately semicircular, and at each end a cross head 8 is provided. An annular 50 guide rib 9 is secured to the casing 1 at approximately the center thereof, the plane of the said rib being parallel with the planes of the ends of the casing, and this rib supports a gear ring 10, the said ring in the 55 present instance being integral with the rib. Each of the cross heads 8 is a species of

casing open at its inner side, and a wheel 11 is journaled in each casing. These wheels 11 engage the opposite faces of the guide rib 9, and other wheels 12 are journaled in 60 extensions 13 at the under side of the casing, the said wheels also engaging opposite sides of the guide rib. The wheels 11 and 12 prevent longitudinal movement of the casing with respect to the guide 7, and a 65 plurality of pairs of wheels 14 is provided for supporting the casing for rotation.

Each pair of wheels 14 is secured to a shaft 15 which is journaled in an extension 16 of the guide, and the members of each 70 pair engage the guide rib 9 on opposite sides of the gear ring 10. The members of each pair of wheels are spaced to receive the teeth of the gear ring 10 between the same, and the pairs are arranged on opposite sides of 75 the center of the guide and on axes parallel with the axis of the guide rib and gear ring. The gear ring is engaged by a pinion 17 secured to a driving shaft 18, the said shaft being journaled in bearings in the extension 80 19. This shaft 18 is driven in any suitable manner, and it will be obvious that when the shaft is rotated the casing will be rotated, riding on the wheels 14 and guided by the wheels 11 and 12.

85 The material is fed into the casing at the high end thereof, by means of a chute 20, and the casing whose lower end is closed by a head 21 integral with the casing, has a discharge opening 22. A funnel-shaped nipple 23 is secured to the head of the casing at the discharge opening and around the same, and the mixing and discharge vane 24 is secured to the said head on the inner face thereof, the said vane extending from 90 the periphery of the casing to the discharge opening. This vane as shown more particularly in Fig. 2, is arched radially of the casing, and at its upper end the vane has a curved conical or tapering extension 25 100 whose large end encircles the opening and is secured to the head of the casing about the said opening. The vane has a continuous curve from one end to the other, the convex surface of the extension being continuous with the convex surface of the body 105 of the vane.

In operation, material is fed into the casing through the chute 20. The casing is rotated in the direction of the convex face 110 of the vane. As the casing rotates the material will engage the convex face of the vane,

slipping off the said convex face, and falling into the lowest part of the casing as the vane moves upwardly. Once during each revolution of the casing the vane will 5 pass through the material in the casing, thoroughly mixing the same, and without any of the said material escaping from the discharge opening because of the fact that the extension of the vane protects and 10 shields the opening.

When the material has been thoroughly mixed the casing is reversed, moving now in such manner that the concave face of the vane first meets the material. The material 15 will now be carried up by the vane and discharged through the discharge opening. Each time the vane moves through the material a portion thereof will be lifted and as the outer or peripheral end of the vane 20 attains a point higher than the inner end, the material will be discharged into the extension 25 and out through the discharge opening into a suitable receptacle. The vane is thus not only a mixing vane but is 25 as well a discharge vane. The arrangement is such that when the mixing drum or casing moves in one direction, the material is mixed and held in the mixer, while when the said drum or casing is turned in the opposite direction it will empty, the contents 30 being discharged through the discharge opening. The entire interior of the drum is free and unobstructed so that none of the material will adhere to the inside of the drum. The inclined arrangement of the 35 drum insures that all of the material will move toward the front or lower end of the drum or casing and the funnel shaped dis- 40 charger with the convex radial vane insures perfect mixing of the ingredients, prevents

adherence of the material to the drum, and discharges the contents of the drum cleanly and rapidly. This drum is of a capacity to hold whatever quantity of material is found most expedient to handle, and in use it will 45 never be necessary to stop for the purpose of cleaning out the drum.

It will be noted that the vane is secured to the lower end of the drum and extends approximately radially from the said opening to near the periphery of the drum adjacent the lower end, and the vane has a cone shaped extension, continuous with the vane, and partially encircling the discharge opening, the vane being curved longitudinally to 50 deflect the material when the drum is rotated in one direction and to carry the material to the discharge opening when the drum is rotated in the opposite direction.

I claim:—

A concrete mixer comprising a drum, means for mounting the drum to rotate in an inclined position, said drum having in its lower end a discharge opening, and a vane secured to the lower end of said drum 65 and extending nearly radially from the said opening to near the periphery of the drum adjacent said lower end, said vane having a cone shaped extension partially encircling the discharge opening, the vane being 70 curved longitudinally to deflect the material when the drum is rotated in one direction and to carry the material to the discharge opening when the drum is rotated in the opposite direction, the vane and the ex- 75 tension being continuous.

HENRY D. WEGE.
